Primary Examiner — Sheryl Lane*Assistant Examiner* — Ieisha N Price(74) *Attorney, Agent, or Firm* — Meunier Carlin & Curfman LLC**CLAIM**

The ornamental design for a sheet pile connector, as shown and described.

DESCRIPTION

FIG. 1 is a front perspective view of a sheet pile connector showing my new design; and,

FIG. 2 is a side view thereof.

The appearance of any portion of the article between the break lines shown in FIG. 1 forms no part of the claimed design.

1 Claim, 2 Drawing Sheets# US D1,043,322 S
